SEAT

Thomas Winrow, Naperville, Ill., assignor to Futorian Corporation, Amsterdam, N.Y.

Filed May 16, 1973, Ser. No. 360,889

Term of patent 14 years

Int. Cl. D6—01

U.S. Cl. D6—62

FIG. 2.

FIG. 1.

FIG. 3.

FIG. 4.

FIG. 1 is a front perspective view of a seat in the form of a chair showing my design;

FIG. 2 is a front perspective view thereof in the form of a sofa;

FIG. 3 is a front perspective view thereof in the form of a loveseat; and

FIG. 4 is a front perspective view of a modified form of the chair shown in FIG. 1.

The side of each embodiment not shown is like the side shown while the backs are conventional.

I claim:

The ornamental design for a seat, as shown and described
